(57) **CLAIM**

The ornamental design for a combined hand massager, speaker, and white noise machine as shown and described.

DESCRIPTION

FIG. 1 is a perspective view of a combined hand massager, speaker, and white noise machine showing my new design; FIG. 2 is another perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is a perspective view of the combined hand massager, speaker, and white noise machine where the combined hand massager, speaker, and white noise machine is in a configuration of use; FIG. 10 is an enlarged view of portion 10 shown in FIG. 3; FIG. 11 is an enlarged view of portion 11 shown in FIG. 8; and, FIG. 12 is an enlarged view of portion 12 shown in FIG. 9. The dash-dash broken lines in the drawings depict portions of the combined hand massager, speaker, and white noise machine that form no part of the claimed design. The dot-dash broken lines represent boundaries of the enlarged portions and form no part of the claimed design.
